UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

RUFFLING SEWING-MACHINE.

1,140,763.

Specification of Letters Patent. Patented May 25, 1915.

Application filed December 18, 1909. Serial No. 532,751.

To all whom it may concern:

Be it known that I, LANSING ONDERDONK, a citizen of the United States, residing at New York, in the county of New York, State 5 of New York, have invented certain new and useful Improvements in Ruffling Sewing-Machines, of which the following is a description, reference being had to the accompanying drawing and to the letters and figures of reference marked thereon.

My invention relates to new and useful improvements in ruffling attachments for sewing machines, and more especially a ruffling attachment for an overseaming machine of the type illustrated, described and claimed in my Patent, No. 932,974, granted June 28, 1910, although it is obvious that certain features of the invention are adapted for use in connection with other types of machines.

An object of the invention is to provide a ruffling attachment which may be quickly thrown into or out of position and operation whenever desired.

A further object of the invention is to provide a ruffling attachment for an overseaming machine, which attachment is so constructed and supported that the attachment, together with its operating mechanism may be readily moved to one side, so as to give access to the parts of the machine in rear of the ruffling attachment.

A further object of the invention is to provide an overseaming machine with a 35 cover plate for certain parts of the stitching mechanism, and a ruffling blade attachment which is connected to the cover plate, and so supported that the attachment, together with the cover plate may be readily 40 turned to one side, so as to give access to the parts of the stitching mechanism in rear thereof.

A further object of the invention is to provide a ruffling mechanism wherein the 45 ruffling blade is positively moved back and forth, and wherein the ruffling mechanism is so constructed and supported that the same may be moved out of operative position whenever desired.

A further object of the invention is to

provide in combination with a stitching mechanism and a trimmer which is located in advance thereof, a ruffling mechanism which shall operate upon the material in advance of the trimming mechanism, which ruffling mechanism may be readily thrown out of operation whenever desired.

These and other objects of the invention will in part be obvious and will in part be hereinafter more fully disclosed.

In the drawings which show by way of illustration one embodiment of my invention,—Figure 1 is a front view of an overseaming machine with my attachment applied thereto, and showing the attachment 65 in inoperative position; Fig. 2 is a similar view with the ruffling mechanism thrown to operative position; Fig. 3 is a view from the end of the machine, showing in dotted lines the ruffling attachment thrown down so as 70 to give access to the parts in rear of the same; Fig. 4 is a view of the support for the ruffling attachment, taken from the back side thereof; Fig. 5 is a detail view, showing the support for the ruffling mechanism 75 and the manner of holding the same in operative position; Fig. 6 is a detail view partly in section, showing the manner of operating the ruffling mechanism from the needle lever; Fig. 7 is a top plan view of 80 the ruffling mechanism, showing the cover plate carried by the support for the ruffling mechanism; Fig. 8 is a detail view, showing the manner of operating the ruffling blade and supporting the separating blade; Fig. 85 9 is a detail view, showing the adjustable arm carried by the needle lever for operating the ruffling mechanism; Fig. 10 is a sectional view through the support for the shaft which carries the ruffling blade; Fig. 90 11 is a detail sectional view, showing the manner of connecting the ruffling attachment to the machine; Fig. 12 is a detail, showing the manner of locking the support for the ruffler in operative position. Fig. 13 95 shows in plan the presser foot, and in dotted lines the relative position of the ruffler blade, the movable trimmer blade, and the deflecting device. Fig. 14 is a side view of the presser foot.

The sewing machine herein illustrated comprises a bed plate 1, from which rises an overhanging arm 2, carrying a needle bar 3 at its forward end which is reciprocated in the usual manner by a needle lever 4.

The needle 5 is carried by the needle bar, and co-operating with said needle is a looper 6. The stitch-forming mechanism herein illustrated is of the overseaming type, wherein a needle loop is carried through the fabric and the thread-carrying looper or spreader co-operates with the needle beneath the work support, while a thread-carrying looper or spreader co-operates with the first thread-carrying looper or spreader and with the needle above the work support.

The particular type of stitch-forming mechanism, however, forms no part of the present invention, except that from certain aspects of the invention, the stitch-forming mechanism should be of an overseaming character.

Located in front of the stitching mechanism is a trimming device, which comprises an upper trimming blade 7, carried by a lever 8, which may be pivoted at the rear side of the machine and operated in the usual manner. Co-operating with the trimmer blade 7 is a stationary member carried by the work support.

The presser foot 9 is carried by the presser bar 10, which is raised or lowered by the usual presser lever 11, or by the lever 12, which is connected with a treadle in the usual manner.

My ruffling attachment is especially adapted for co-operation with a machine of the above character. Said attachment comprises a base plate 13, on which the bed plate 1 of the machine may rest. Said base plate 13 is secured to the bed plate of the machine by bent arms 14, 15, which extend up over the bed plate and are secured to the base plate by suitable screws. A similar arm 16 is arranged at the rear of the machine.

The base plate 13 has a standard 17, projecting therefrom, to which is pivoted the support 18 for the ruffling mechanism. The support 18 is provided with upwardly projecting arms 19 and 20, in which is loosely mounted a sliding bar 21. Said bar is preferably rectangular in cross section, and the openings in the arms 19 and 20 to receive the bar 21 are of similar shape. The bar 21 is free to slide longitudinally in the arms 19 and 20. Said bar 21 carries an adjustable arm 22 at its forward end, which projects downwardly and then laterally at 23, and carries a stripper blade 24.

The sliding bar 21 has an opening extending longitudinally through the same, and receives a shaft 25 (see Fig. 10). The shaft 25 at its forward end has an arm 26, secured thereto by a split collar and clamping

screw 27, so that the arm 26 is oscillated back and forth with the shaft 25.

The shaft 25 is a hollow shaft and extending therethrough is a rod 25^a, which supports at an outer end, an arm 28. At the lower end of the arm 28 is a ruffler support 29, which is pivoted to said arm by a screw 30. A spring 31 is coiled about the screw 30, and one end of the spring 31 engages the arm 28, while the other end engages the upwardly projecting arm of the ruffler support 29. A ruffling blade 32 is carried by the ruffler support 29. The spring 31 normally tends to rotate the ruffler support, so as to lift the ruffling blade 32 away from the fabric. A stop 33 limits the upward movement of the ruffling blade.

The arm 26 carries a laterally projecting lug 34 at its lower end, which is provided with an adjustable screw 35, which is adapted to contact with the upper end of the ruffler support 29. The upper end of the arm 26 is provided with a laterally projecting lug 36, which carries an adjustable screw 37. A locking nut 38 holds the screw 37 in its adjusted positions. The screw 37 is located in the path of an upwardly projecting finger 39, carried by the arm 28.

It will readily be seen that if the arm 26 is oscillated in the direction of the arrow, Fig. 8, the screw 35 will be brought into contact with the upper end of the ruffler support, and said support will be turned about its pivotal point 30, so as to bring the ruffling blade into contact with the fabric. A further movement of the arm 26 will oscillate the arm 28 about its pivotal support and carry the ruffling blade forward to the limit of its forward movement. This movement of the ruffling blade is the usual gathering or fulling movement.

When the shaft 25 is oscillated in the opposite direction, the screw 35 will immediately be moved away from the ruffler support 29, which will allow the spring 31 to oscillate said support about its pivotal point, thus lifting the ruffler blade or tending to lift the same off from the fabric. A further movement of the arm 26 in this direction causes the screw 37 to contact with the finger 39, and oscillate the arm 28 so as to retract the ruffler blade.

It will thus be seen that the ruffler blade by the oscillation of the shaft 25 is moved back and forth positively, and is held positively in engagement with the material, as it is moved forward, while all pressure of the same upon the material is relieved during the return stroke of the ruffler blade.

As a means for oscillating the shaft 25, I have provided the same with the projecting arm 40, which is clamped to the shaft 25 by means of a screw 41. Said arm at its outer end is forked, so as to provide the spaced fingers 42 and 43.

The needle lever 4 is provided with an operating arm 44, which is secured thereto by means of a bolt 45. Said arm 44 projects above the pivot bolt and overhangs the needle lever 4. A set screw 46 passes through one portion of the arm 44, while a set screw 47 passes through the other portion thereof. The said set screws engage the upper surface of the needle lever 4, as clearly shown in Fig. 6.

The arm 44 at its lower end is bent laterally as shown in Fig. 9, to form an operating abutment 48 for the ruffling mechanism. Beyond the abutment 48 the arm is tapered substantially to a point 49. When the supporting bar 21 for the ruffling mechanism is moved to the position shown in Fig. 2, the fingers 42 and 43 of the arm 40 engage over the abutment 48 of the operating arm 44 carried by the needle lever 4. As the needle lever is vibrated up and down, the abutment 48 will thus, through the arm 40, oscillate the shaft 25.

When, however, the supporting rod 21 is moved to the position shown in Fig. 1, the operating arm 40 is moved away from the abutment 48, so that the vibrations of the needle lever do not oscillate the shaft 25. The tapered end 49 of the operating arm 44 serves as a means to readily cause the arm 40 to be moved into operative engagement with the abutment 48.

A spring 50 is secured at one end to the support 18 and at its other end to the arm 22, supporting the stripper blade. Said spring normally tends to hold the bar 21 in the position shown in Fig. 1, and the ruffling mechanism out of operative position.

A lever 51 is pivoted at 52 to a bracket 53 mounted on the standard 17. The upper end of said lever is provided with a roller 54, while the other end of said lever 51 may be connected to a suitable treadle or knee shift. A spring 55 is mounted upon the standard 17 and engages the lever 51 and normally holds the same in raised position against the stop 56. An adjustable stop 56^a limits the downward movement of said lever.

An arm 57 is pivoted at its lower end to a bracket 58, carried by the standard 17, and at its upper end is forked, so as to straddle the supporting shaft 25, for the ruffling mechanism. Said forked end of the arm 57 is connected to suitable screws 59, carried by a collar 59^a on the shaft 25. When the lever 51 is depressed, the roller 54 engages the arm 57, and swinging the same about its pivotal support, forces the supporting bar 21 to the left, as viewed in Fig. 1, so as to bring the ruffler into operative position.

As above noted, when the ruffler is moved to operative position, the fingers 42 and 43 of the operative arm 40 engage the abutment 48 of the operating arm 44 carried by the needle lever 4.

When the lever 51 is released, the spring 55 raises said lever against the stop 56, and the spring 50 throws the supporting bar 21 to the right, as viewed in Fig. 1, thus throwing the ruffling mechanism out of operative position.

The rod 25^a is provided with a collar 60, which is secured thereto by any suitable means (see Fig. 10). A disk 61 mounted on the rod 25^a, is provided with a forked end 62, which straddles the pivoted arm 57. Between the disk 61 and the fixed collar 60, is a wood fiber disk 62. A second wood fiber disk 63 is also placed loosely on the shaft 25^a, and bearing against said disk 63 is a metal plate 64.

A spring 65 surrounds the outer end of the rod 25^a, and a thumb nut 66 compresses the spring 65 against the plate 64.

By adjusting the thumb nut 66, the tension of the spring on the plate 64 may be varied. The purpose of the wood fiber disks which are located on each side of the stationary disk 62, is to provide sufficient friction so as to control the movements of the crimping or ruffling blade.

The hollow shaft 25 moves loosely about the rod 25^a, which supports the ruffling blade and the wood fiber disks hold the supporting rod 25^a against movement until the operating screws 34 or 36 contact with the arm 28 to positively move the same.

It will thus be seen that the ruffler will be held at the forward end of its movement, by means of the tension on the supporting rod 100 until the ruffler support has been turned by means of the spring 31 to lift the ruffler blade, and the tension disks will prevent overthrowing of the ruffling blade at the other end of its stroke.

As a means for holding the arm 40 in proper relation to the abutment 48, I have provided stop arms 67, 68, which are secured to the bracket arm 20 by suitable screws 69, 69.

The support 18 for the ruffler is pivoted to the standard 17, as above noted, and when in raised position, the adjustable bolt 77^a rests against a lug 70. As a means for holding said support 18 in raised position, 115 I have provided a locking latch 71, which carries an adjustable screw 72 at one end, which engages a cam plate 73 carried by the support 18. A finger piece 74 assists in the manipulation of the latch 71. When the handle is thrown into the position shown in Fig. 5, the screw 72 engages the cam shoulder 73, and locks the support 18 firmly against the supporting lug 70.

An overseaming machine of the character herein shown is usually provided with the cover plate which is located between the trimming mechanism and the point of stitching, so as to deflect away the trimmed-off strip. This cover plate protects the 120

parts of the stitching mechanism from the portions of the fabric which are being trimmed off.

I have shown herein the cover plate as carried by the support for the ruffling mechanism, so that when the ruffling mechanism is thrown down to give access to the parts behind the same, the cover plate is also moved with the ruffling mechanism away from the stitching elements, so that by a single operation the parts may be uncovered.

The cover plate 75 which is also curved to form a diverting guide or deflecting plate for the trimmed-off strip, is herein shown, (see Fig. 4) as carried by an arm 76, which is provided with slots 77, and the screws 78, 79 through the slots 77, secure the cover plate to the back of the support 18 for the ruffling mechanism.

A spring 79 is secured at one end to the arm 20 of the support 18, and at its other end to the cover plate. Said spring normally holds the cover plate retracted, as shown in Fig. 4. After the ruffling mechanism has been turned up to operative position, it is then desirable to crowd the cover plate over against the edge of the work support, so as to prevent the trimmed-off portions from passing between the end of the cover plate and the work support.

As a means for moving the cover plate against the work support, I have provided said cover plate with an adjustable arm 80, which is secured to the cover plate support 76 by screws 81. The arm 80 projects around at one side of the support 18, and carries a downwardly projecting portion 82. The latch 71 is provided with an outwardly extending arm 83, which engages the portion 82 carried by the cover plate support when the handle is rotated, so as to lock the support 18 in position. It will thus be seen that when the support 18 is swung to operative position, and the latch 71 rotated to lock the same therein, the cover plate will be crowded over against the work support against the tension of the spring 79. As soon as the latch 71 is turned in the opposite direction to release the support 18, the spring 79 will throw the cover plate away from the work support, so that the cover plate may be readily moved with the ruffling mechanism, and thus uncover the parts of the machine behind the same. In this type of machine, the work support is usually provided with a movable extension, extending to the right of the line of feed as viewed in Fig. 1. In the place of this usual movable extension for the work support, I have mounted the extension 84 on a bracket arm 85 carried by the support 18 for the ruffling mechanism. When the ruffling mechanism is thrown down to expose the parts of the

machine, the extension 84 is carried therewith and when the ruffling mechanism is thrown to its closed position, the extension 84 is then brought up into proper position relative to the work support.

The feed dogs 85^a extend forward to the position where the ruffling blade and trimmer blade operate upon the fabric, as shown in Fig. 7. In order that the stripper blade or ruffling blade may be lifted up over the feed dog when it is moved into operative position, I have provided the bed plate with a raised portion 86 (see Figs. 5, 7 and 8), which operates to lift the stripper blade as it is moved laterally, so as to bring the same above the feed dogs.

The raised portion 86 is adjustably secured to the extension of the work support by a suitable screw 86^a (see Fig. 7). The right hand side of the raised portion 86, as shown in Fig. 5, is tapered while the other edge of the raised portion is provided with a vertical wall 86^b. This vertical wall of the raised portion may serve as an edge guide for guiding the edge of the material which is to be trimmed, ruffled, and stitched.

In certain classes of work, it is desired to trim off merely the rough projecting threads and in such cases said wall 86^b, will serve to guide the edge of the material so that the projecting threads will be cut by the trimmer.

The inclined face of the raised portion 86 as above noted, will serve as a means for guiding the stripper blade so as to raise it above the edge of the fabric and will maintain its line of travel into and out of operative position.

The presser foot 9 is provided with the usual stitch finger 9^a. The front or toe of the presser foot 9^a is slightly deflected upwardly and the ruffling blade operates under the front end of the toe. The position of the ruffling blade when in action is indicated in dotted lines in Fig. 13. I have also indicated in dotted lines in this figure, the position of the movable trimmer blade 7, and the deflecting device 75, which engages and deflects the trimmed off strip. The trimmed off strip engages the deflecting plate 75 and passes down through the space formed in the work support between said deflecting plate 75 and the extension 84 (see Fig. 8). Said deflecting plate extends underneath the extension, thus forming a channel to carry the trimmed off strip forward beneath the ruffler. The position of the stripper blade may readily be adjusted by loosening the screw which connects the arm 22 to the supporting member 21. The raised portion 86 for guiding the edge of the fabric, and for guiding the stripper blade as it is moved into and out of action, may be readily adjusted by loosening the screw 86^a.

A further operation of my device, will be apparent from the above description. It will be seen that I have provided a sewing machine of the overseaming type with a ruffling mechanism which may be readily thrown into or out of operation, and that the ruffling operation may readily be turned away from the machine, so as to expose the parts in the rear of the same.

10 Having thus particularly described my invention, what I claim as new and desire to secure by Letters Patent is:—

1. The combination with a work support, stitch-forming mechanism, a trimmer operating in advance of the stitch-forming mechanism, a ruffler operating upon the material in advance of the trimmer, and means for moving the ruffler laterally out of engagement with the material without stopping the 20 stitch-forming mechanism.

2. The combination with stitch-forming mechanism, of a trimmer operating in advance of the stitch-forming mechanism, a ruffler engaging the material in advance of the trimmer, means for operating the ruffler, and means for moving the ruffler laterally out of engagement with the material and for disconnecting the ruffler from its operating mechanism without stopping the 30 stitching mechanism.

3. The combination with overseaming stitch-forming mechanism, of a trimmer operating in advance of the overseaming mechanism and a ruffler operating upon the material in advance of the trimmer and means for moving said ruffler laterally out of engagement with the material without stopping the overseaming mechanism.

4. The combination with a work support, 40 stitch forming mechanism, a cover plate in front of certain parts of the stitch forming mechanism for covering the same, a ruffling mechanism having parts thereof in front of said cover plate, and means whereby said ruffling mechanism and said cover plate may be moved away from the parts of the machine in rear thereof, whereby access to the same may be had.

5. The combination with a work support, 50 an overhanging arm, a needle lever carried thereby and a needle vibrated by said needle lever, of a ruffling mechanism, including a ruffling blade, and means for operating said ruffling blade from said needle lever to give 55 said ruffling blade positive movement in both directions, a support for said ruffling mechanism, and means whereby said support, together with said ruffling mechanism, may be moved away from the needle lever 60 without stopping the needle.

6. The combination of a sewing machine, including a work support, an overhanging arm and stitch forming mechanism, of a ruffling attachment including a supporting

base on which the base of said sewing machine may be secured, a standard rising from said base, a ruffling mechanism carried by said standard and means for operating said ruffling mechanism from a moving part of the machine and means whereby said ruffling 70 mechanism may be moved relative to said standard away from the stitch-forming mechanism, so as to render the same inoperative.

7. The combination with a sewing machine, including a work support, an overhanging arm, and stitch forming mechanism, of a ruffling attachment including a supporting base, a standard rising therefrom, a support pivoted to said standard, 80 ruffling mechanism carried by said support, means for operating said ruffling mechanism from a moving part of the machine, and means whereby said ruffling mechanism may be moved relative to said support away from 85 the stitch forming mechanism, so as to render the same operative or inoperative.

8. The combination with a sewing machine including a work support, an overhanging arm and stitch forming mechanism, 90 of a ruffling attachment including a supporting base, a standard rising therefrom, a support on said standard, ruffling mechanism carried by said support, means for operating said ruffling mechanism from a moving part 95 of the machine, and means whereby said ruffling mechanism may be moved relative to said support away from the stitch forming mechanism so as to render said ruffling mechanism operative or inoperative, said 100 support being pivoted on the standard whereby the ruffling mechanism may be moved away from the overhanging arm.

9. The combination with a sewing machine, including a work support, an overhanging arm and stitch forming mechanism, of a ruffling attachment including a supporting base, a standard rising therefrom, a support on said standard, a ruffling mechanism carried by said support, means 105 for operating said ruffling mechanism from a moving part of the machine, a lever pivoted to said standard for moving said ruffling mechanism in its support so as to bring the same into operative position relative to the stitch forming mechanism and means for moving said ruffling mechanism in its support so as to render the same inoperative when said lever is released, said 110 support being pivoted on the standard 115 whereby the ruffling mechanism may be moved away from the overhanging arm.

10. The combination with a sewing machine, including a work support, an overhanging arm, and stitch forming mechanism, of a ruffling mechanism, a support for said ruffling mechanism, means whereby said support may be moved away from the over-

- hanging arm, said work support having an extension rigidly secured to the support for the ruffling mechanism, whereby when said support is moved, said extension is moved therewith.
11. The combination with a sewing machine including a work support, an overhanging arm, and stitch forming mechanism, of a ruffling mechanism, a support for said ruffling mechanism, means whereby said support may be moved away from the overhanging arm, said work support having an extension rigidly secured to the ruffling mechanism support, whereby when the latter is moved, said extension is moved therewith, said support carrying also a cover plate for the mechanism of the machine in rear thereof.
12. A sewing machine including in combination, a needle lever, a needle operated thereby, a ruffling mechanism including a ruffling blade, means for operating said ruffling blade, positively back and forth from said needle lever, and means for moving said ruffling blade laterally, said lateral movement of the ruffling blade disconnecting the same from the needle lever so that the same is rendered inoperative.
13. The combination of a needle lever, a needle operated thereby, a ruffling mechanism including a ruffling blade, an arm pivoted to said needle lever for operating said ruffling blade, means for adjusting the position of said arm about its pivotal support for varying the stroke of the ruffling blade.
14. The combination with a needle lever, a needle operated thereby, of a ruffling mechanism including a ruffling blade, means for moving said ruffling blade back and forth positively, including an arm having spaced projections at its outer end, an arm pivoted to the needle lever, and having a projecting portion adapted to engage between the projecting portions on said first named arm.
15. The combination with a needle lever, a needle operated thereby, of a ruffling mechanism including a ruffling blade, means for moving said ruffling blade back and forth positively, including an arm having spaced projections at its outer end, an arm pivoted to the needle lever, and having a projecting portion adapted to engage between the projecting portions on said first named arm, and means for moving said arm, connected to the ruffling mechanism, laterally, so that the same is connected to or disconnected from the operating arm carried by the needle lever.
16. The combination of a work support, stitch forming mechanism, a feed dog moving upwardly through the work support to feed the fabric, a ruffling mechanism including a stripper blade and a ruffling blade, means for moving said stripper and ruffling blades laterally, and means operating on the stripper blade as it is moved laterally for preventing the stripper blade from striking the side of the feed dog.
17. The combination with a work support and stitch forming mechanism, a cover plate for covering certain parts of the stitch forming mechanism, a ruffling mechanism, a support for said ruffling mechanism, means for slidably supporting said cover plate on said ruffer support, a spring for moving said cover plate laterally away from the work support, and means for moving said cover plate against the work support when the ruffer support is in operative position.
18. The combination with a work support and stitch forming mechanism, a cover plate for covering certain parts of the stitch forming mechanism, a ruffling mechanism, a support for said ruffling mechanism, means for slidably supporting the cover plate on said ruffer support, a spring for moving said cover plate laterally away from the work support, and means for moving said cover plate against the work support and for simultaneously locking the ruffer support in operative position.
19. The combination with a work support, a cover plate, a ruffer mechanism, a support for said ruffer mechanism, means for supporting said cover plate on the support for the ruffer mechanism, said work support having an extension, means for rigidly supporting said extension by said ruffer support, and means whereby the ruffer support together with the extension for the work support and the cover plate, may be moved away from the parts of the machine in rear thereof, so that access thereto may be had.
20. A ruffling attachment including in combination a ruffling blade, a supporting arm to which said ruffling blade is pivoted, a spring normally tending to rotate said ruffling blade on its pivotal support, whereby the same is held out of engagement with the material, an oscillating arm, a stop carried thereby for engaging the shank of the ruffling blade, whereby it is turned into engagement with the material and subsequently moved forward to gather said material.
21. A ruffling attachment including in combination, a ruffling blade, a supporting arm to which said ruffling blade is pivoted, a spring normally tending to rotate said ruffling blade on its pivotal support, whereby the same is held out of engagement with the material, an oscillating arm, a stop carried thereby for engaging the shank of the ruffling blade, whereby it is turned into engagement with the material and subsequently moved forward to gather said material, and means for moving the ruffling blade support out of the line of feed.
22. A ruffling attachment including in

combination, a ruffling blade, a supporting arm to which said ruffling blade is pivoted, a spring normally tending to rotate said ruffling blade on its pivotal support where-
5 by the same is held out of engagement with the material, an oscillating arm, a stop carried thereby for engaging the shank of the ruffling blade, whereby it is turned into engagement with the material and subse-
10 quently move to gather said material, means for moving the ruffling blade support out of the line of feed, and means for swinging the ruffling blade and support in a direction substantially at right angles to its move-
15 ment away from the line of feed.

23. A ruffling attachment including in combination a ruffling blade, a supporting arm to which said ruffling blade is pivoted, a spring normally tending to rotate said ruffling blade on its pivotal support, where-
20 by the same is held out of engagement with the material, an oscillating arm, a stop carried thereby for engaging the shank of the ruffling blade whereby it is turned into engagement with the material and subse-
25 quently moved forward to gather said material, a second stop carried by said oscillating arm for positively withdrawing said ruffling blade.

30 24. A ruffling attachment including in combination a ruffling blade, a rod supporting said ruffling blade, a friction device for holding said rod against too free movement, an oscillating arm, stops carried by said oscillating arm, for oscillating the ruffling blade back and forth.

25. A ruffling attachment including in combination, a ruffling blade, a rod, an arm secured to said rod and carrying said ruff-
40 fling blade, a collar secured to said rod, a disk carried by said rod, means for holding said disk from rotating, a friction washer interposed between said disk and said collar, means for varying the pressure on said friction washer, and means for intermittently oscillating said rod, whereby said ruffling blade is moved back and forth.

26. A ruffling attachment including in combination a ruffling blade, an arm on which said ruffling blade is pivotally sup-
50 ported, a rod to which said arm is attached, a hollow shaft surrounding said rod, a sup-
porting bar in which said shaft and said rod are supported, means for oscillating said shaft, means carried by said shaft for oscillating said rod.

27. A ruffling attachment including in combination, a ruffling blade, an arm on which said ruffling blade is pivotally sup-
60 ported, a rod to which said arm is attached, a hollow shaft surrounding said rod, a sup-
porting bar in which said shaft and said rod are supported, means for oscillating said shaft, means carried by said shaft for oscil-
65 lating said rod, and means for moving said

bar longitudinally, whereby said ruffler may be rendered operative or inoperative.

28. A ruffling attachment including in combination, a ruffling blade, a supporting shank to which said ruffling blade is at-
70 tached, an arm to which said shank is piv-
otally connected, a spring engaging said shank, and operating to normally lift the ruffling blade off the material, a rod to which said arm is secured, a collar secured to said rod, a disk loosely engaging said rod, a friction washer between said disk and said collar, means for yieldingly pressing said disk against said friction washer, a hollow shaft through which said rod extends, means for 80 oscillating said hollow shaft, an arm carried by said hollow shaft, a stop carried by said arm and engaging the shank supporting said ruffling blade, whereby the ruffling blade by the oscillation of said shaft, is 85 brought into contact with the material and by a further movement of said shaft, is moved forward to gather the material.

29. A ruffling attachment including in combination, a ruffling blade, a supporting shank to which said ruffling blade is at-
90 tached, an arm to which said shank is piv-
otally connected, a spring engaging said shank and operating to normally lift the ruffling blade off the material, a rod to which 95 said arm is secured, a collar secured to said rod, a disk loosely engaging said rod, a friction washer between said disk and said collar, means for yieldingly pressing said disk against said friction washer, a hollow shaft 100 through which said rod extends, means for oscillating said hollow shaft, an arm carried by said hollow shaft, a stop carried by said arm and engaging the shank supporting said ruffling blade, whereby the ruffling 105 blade by the oscillation of said shaft, is brought into contact with the material and by a further movement of said shaft, is moved forward to gather the material, and a second stop carried by the arm secured to 110 the hollow shaft, and engaging the arm supporting the ruffling blade, for retracting said ruffling blade.

30. In a sewing machine, the combination of a needle, a trimming device located in advance of said needle, a deflecting plate located between said needle and said trimming device, a ruffling device located in advance of said trimming device to ruffle the material in advance of the trimming operation said 115 deflecting plate being carried by the same support which carries the ruffling device.

31. In a sewing machine, a ruffling device for ruffling the fabric, a trimming device for trimming the edge of the ruffled fabric, 120 a deflecting device to deflect the trimmed off strip away from the sewing mechanism, and overseaming mechanism for forming a stitch around the trimmed edge of the ruffled fabric said deflecting plate being car- 125 130

- ried by the same support which carries the ruffling device.
32. In a sewing machine, a work plate, a ruffling device including a stripper blade, means whereby said ruffling device can be moved from ineffective to effective position, a projection on said work plate located at one side of the ineffective position of the ruffling device, whereby in the movement of the ruffling device, the stripper blade will be held positively elevated.
33. In a sewing machine, a diverting guide, a ruffling device, a presser foot provided with a lateral extension, means for moving said ruffling device out of operative position, a latch for locking said ruffling device in position, and means operable upon the releasing of said latch for moving said diverting guide out of the path of said presser foot extension to enable the ruffling device to be moved from operative position.
34. In a sewing machine, a diverting guide and means to move it, a presser foot having a lateral extension, a latch for operating said guide one way and a spring for moving said guide as soon as the control of the latch is released to enable the diverting guide to pass the presser foot extension.
35. In a sewing machine, a ruffling device which can be moved from operative to inoperative position, a latch for holding said device in operative position, a diverting guide, said latch also operating to move said diverting guide into operative position as said movable device is locked in operative position.
36. In a sewing machine, a ruffling device, means to move said ruffling device from operative to inoperative position, a stop to determine the operative position and a latch carrying an adjustable part to maintain said device in operative position.
37. In a sewing machine, a diverting guide, a ruffling device, a latch for holding said ruffling device in position, and means operated by said latch for moving said diverting guide into or out of operative position.
38. In a sewing machine, a diverting guide, a ruffling device, a latch for holding said ruffling device in position, and means operated by said latch for moving said diverting guide into or out of operative position, said diverting guide being under control of a spring.
39. In a sewing machine, a ruffling device including a ruffling blade and a stripping blade, and a diverting guide, and a work plate extension, said ruffling and stripping blades, diverting guide and work plate extension, having means to move them from operative to inoperative position.
40. In a sewing machine, a ruffling device including a ruffling blade, normally inactive when in inoperative position, means for moving said blade laterally into operative position and for automatically throwing it into action.
41. In a sewing machine, a ruffling device, including a ruffling blade, means to move said ruffling blade laterally of the line of feed, said means including a lever and stops for limiting the movement of said lever.
42. The combination with a sewing machine including a work support, an over-hanging arm, stitch-forming mechanism, a ruffling attachment comprising a supporting device, a standard rising therefrom, a support on said standard, a ruffling mechanism carried by said support, means for operating said ruffling mechanism from a moving part of the machine, a lever pivoted to the standard for moving said ruffling mechanism on its support, so as to bring the same into operative position relative to the stitch-forming mechanism, and means for moving said ruffling mechanism on its support, so as to render the same inoperative when said lever is released.
43. In a sewing machine, the combination of a work support, a trimmer, a deflecting device located in rear of the cutting edge of the trimmer, a ruffling device located in advance of said trimmer and deflecting device, said work support having an open space between the ruffling device and deflecting device for the passage of the trimmed off strip.
44. A sewing machine including in combination, stitch-forming mechanism, a ruffling device, a trimming device, said ruffling and trimming devices being located in front of the stitch-forming mechanism, a guide for the edge of the material being ruffled, trimmed and stitched, and means for moving the ruffling device laterally for rendering said ruffling device ineffective.
45. In a sewing machine, stitch-forming mechanism, a ruffling device including a ruffling blade and a stripping blade, means for operating the ruffling blade, and means for moving the ruffling blade laterally from an operative to an inoperative position relative to the stitch-forming mechanism said lateral movement of the ruffling blade disconnecting said ruffling blade from its operating mechanism.
46. In a sewing machine, a stitch-forming mechanism, a ruffling device including a ruffling blade, a stripping blade, means for operating the ruffling and stripping blades from operative to inoperative position, including a lever, and devices operated thereby for disconnecting the ruffling blade from its operating mechanism when said ruffling blade is moved to inoperative position.
47. In a sewing machine, a ruffling device, including a ruffling blade, means for vibrating said ruffling blade, said vibrating means

including a device to give the blade a forward and backward movement and also a vertical movement, whereby the fabric is engaged and released positively by the ruffling blade and means for moving the ruffling blade laterally for rendering the same ineffective.

In testimony whereof I affix my signature, in presence of two witnesses.

LANSING ONDERDONK.

Witnesses:

R. A. OSWALD,
AUG. J. WOHLPART.
